United States Patent Office

Des. 185,430
Patented June 9, 1959

185,430

SKETCHING DEVICE

Jack Frost, Needham, Mass.

Application October 10, 1958, Serial No. 52,924

Term of patent 14 years

(Cl. D29—20)

Fig. 4.

Fig. 1 is a top plan view of a sketching device showing my new design;

Fig. 2 is a front elevational view thereof;

Fig. 3 is a left side elevational view thereof; and

Fig. 4 is an enlarged perspective view thereof.

The tripod legs are broken in Figs. 2, 3, and 4 for convenience of illustration.

I claim:

The ornamental design for a sketching device, substantially as shown and described.
